UNITED STATES PATENT OFFICE.

WILLIAM H. BURDEN, OF DETROIT, MICHIGAN.

SHADE OR CANOPY SUPPORTING BRACKET.

No. 818,937.

Specification of Letters Patent.

Patented April 24, 1906.

Application filed September 30, 1905. Serial No. 280,840.

To all whom it may concern:

Be it known that I, WILLIAM H. BURDEN, a citizen of the United States of America, residing at Detroit, in the county of Wayne 5 and State of Michigan, have invented new and useful Improvements in Shade or Canopy Supporting Brackets, of which the following is a specification.

This invention relates to improvements in 10 brackets for adjustably attaching shades or canopies to baby-carriages and go-carts, the object of the invention being to provide a bracket of this character which is simple of construction, applicable to either of these 15 types of vehicles, and adapted to support the shade firmly and securely in adjusted position.

Another object of the invention is to so 20 construct the bracket that it may be employed as a hanger from which a shopping-bag or other similar parcel-holder may be suspended.

With these and other objects in view the 25 invention consists of the novel construction and combination of parts hereinafter fully described and claimed, reference being had to the accompanying drawings, in which—

Figure 1 is a side elevation of a portion of a 30 baby-carriage, showing the application of the invention thereto. Fig. 2 is a vertical section through the back of the carriage and the bracket. Fig. 3 is a perspective view of the bracket detached. Fig. 4 is a similar view of the rear plate of the bracket, showing a modified mode of connecting the bracket-arm thereto.

Referring now more particularly to the 40 drawings, the numeral 1 designates the body of a baby-carriage, and 2 the back thereof.

The bracket comprises front and rear 45 plates 3 and 4, preferably of a rectangular form, but which may be of any suitable form and material. These plates are arranged to bear, respectively, against the front and rear surfaces of the vehicle-back 2 and are provided at their corner portions with openings 50 for the passage of screw-bolts 5, which also extend through the back 2 and carry nuts 6, whereby the plates may be firmly clamped in position. This construction renders the 55 bracket available for application to any of the ordinary types of baby-carriages or go-carts.

The outer or rear plate 4 supports a 60 bracket-arm 7, which is provided at its inner end with an eye 8 and at its outer end with

a head or enlargement 10, formed with a vertical passage 11, intersected by a screw-threaded aperture 12, extending transversely through the rear portion of the head, said 60 aperture 12 being adapted to receive a winged clamping-screw 13. The eye 8 is adapted to fit between two apertured ears 14, formed upon the plate 4, and is pivotally connected thereto by a screw-bolt 15, provided at its 65 lower end with a clamping-nut 16. Instead of being pivotally connected with the plate 4 the bracket-arm 7 may be rigidly attached to the plate, as indicated at 8' in Fig. 4.

The socket or passage 11 is adapted to receive the supporting arm or rod 17 of a suitable shade or canopy which is vertically adjustable therein and adapted to be clamped in adjusted position by the set-screw 13. 70 The pivotal connection between the bracket-arm and plate 4 permits the shade to be adjusted laterally and clamped in such adjusted position by the set-screw 16, as will be readily understood. By this means the shade 75 may be more effectually adjusted to adapt it 80 to shield the eyes and face of the occupant of the carriage.

The bracket-arm 7 is so constructed as to adapt it to be used as a hanger or support from which a reticule, shopping-bag, or other 85 similar container or parcel-holder may be suspended. To this end the body portion 18 of said arm is made of sufficient length for the purpose and is preferably reduced to receive and hold the handles of the receptacle between the eye 8 and head 10 and prevent the same from shifting longitudinally thereon. In order to apply the bag or parcel-holder, the clamping-screw 13 is relaxed, the rod 17 removed from the passage 11, and handles of 90 the bag slipped over the head 10 and upon the reduced portion 18 and the rod 17 then reapplied and clamped by the set-screw 13. The rod 17 will thereupon act as a guard or stop to retain the bag in position and prevent 100 its loss. By this means a shopping-bag or other similar article may be conveniently carried, leaving both hands of the lady or attendant free to manipulate the carriage and handle her dress. In addition to this convenience liability of theft of the bag is reduced, as the time necessary to remove the 105 rod 17 to enable the bag to be detached from the bracket-arm would deter an unauthorized person from attempting to remove the 110 bag.

It will of course be understood that the

parts of the bracket may be made of any suitable material and ornamented as desired and that the outer clamping-plate may serve as an escutcheon-plate on which the name of 5 the owner or occupant of the carriage may be engraved or applied in any preferred manner.

Having thus described the invention, what is claimed as new is—

1. A shade-supporting bracket for baby-carriages and go-carts comprising inner and outer clamping-plates, means for attaching the same to the body of the vehicle, and a bracket-arm carried by the outer clamping-plate and provided with means for securing 15 the supporting member of the shade thereto.

2. A shade-supporting bracket for baby-carriages and go-carts comprising inner and outer clamping-plates, means for connecting the same to the body of the vehicle, and a bracket-arm pivotally connected to the outer 20 plate and provided with means for securing the supporting member of the shade thereto.

3. A shade-supporting bracket for baby-carriages and go-carts comprising a body 25 portion adapted to be secured to the body of

the vehicle, a clamping-arm connected with said body portion and provided with a head and clamping device for securing the supporting member of the shade thereto, the part of the arm between the body portion of the 30 bracket and head being constructed to serve as a support for a parcel-holder.

4. A shade-supporting bracket for baby-carriages and go-carts comprising inner and outer clamping-plates, means for securing the 35 same to the body of the vehicle, a bracket-arm connected at one end with the outer plate and provided at its outer end with a head having a vertical passage, the portion of the arm between its inner end and head being constructed to serve as a support for a parcel-holder, and a clamp carried by the head, substantially as described. 40

In testimony whereof I affix my signature in presence of two witnesses.

WILLIAM H. BURDEN.
